DESIGN FOR A TEXTILE FABRIC OR SIMILAR ARTICLE

William Laird Turner, Hollis, N. Y., assignor to Cohn-Hall-Marx Co., New York, N. Y.

Application April 16, 1937, Serial No. 68,811

Term of patent 3½ years

To all whom it may concern:

Be it known that I, William Laird Turner, a citizen of the United States of America, residing at 110-09 200th Street, Hollis, Long Island, New York, have invented a new, original, and ornamental Design for a Textile Fabric or Similar Article, of which the following is a specification, reference being had to the accompanying drawing, forming a part thereof.

The figure is a plan view of a textile fabric showing my new design. The dot and dash lines on the drawing outline substantially a design unit, which unit is repeated in regular succession as indicated by the extensions beyond the unit boundaries.

I claim:

The ornamental design for a textile fabric or similar article as shown and described.

WILLIAM LAIRD TURNER.
